CLAIM

The ornamental design for an electronic device stand, as shown and described.

DESCRIPTION

FIG. 1 is a perspective view of an electronic device stand showing our new design;

FIG. 2 is a front elevational view thereof;

FIG. 3 is a rear elevational view thereof;

FIG. 4 is a right side view thereof;

FIG. 5 is a left side view thereof;

FIG. 6 is a top plan view thereof;

FIG. 7 is a bottom plan thereof; and,

FIG. 8 is an exploded view thereof.

The broken lines in the drawings illustrate portions of the electronic device stand that form no part of the claimed design.
